TROUSERS HANGER

Willard H. Baugh, Dearborn, Mich.

Continuation of application Serial No. 706,485,
January 13, 1934. This application November
7, 1936, Serial No. 109,631

4 Claims. (Cl. 223—96)

This invention relates to clothes hangers, more particularly hangers for men's trousers and is a continuation of my application Serial No. 706,485, filed January 13, 1934.

- 5 An object of the invention is to provide a comparatively simple and inexpensive structure for the purpose of such character of construction that the trousers may be suspended by the end of the legs.
- 10 A further feature and object of the invention is to provide a structure, devoid of manipulable clamping devices and the like commonly known in this art for supporting trousers by the leg ends, into which the leg ends may be introduced or 15 from which they may be removed with greater ease and without necessity of manipulation of movable parts.

It is also an object of the invention to provide a structure of the character heretofore stated 20 for supporting two pairs of trousers in parallel relation on opposite sides of a central supporting member by which they may be hung in inverted position, and a further feature and object of the invention is to provide a device that is adjustable in length whereby trouser legs of different widths may be conveniently supported by the 25 hanger.

Also, a feature of the invention resides in the 30 construction of the clamping means by which pressure is applied uniformly to the leg ends of the trousers throughout a considerable surface and thereby avoiding a clamping pressure at a small area which would tend to form an indentation and permit sagging between the parts of 35 support.

It is also a feature and object of the invention to provide a trousers hanger of a form providing 40 a spring clamping means operable to engage the cuff at the end of the trousers legs or to engage the trouser legs beneath the cuffs when the trousers are in an inverted position so that edges of the cuffs may also rest upon the upper 45 face of the device.

These are other objects and novel features of 45 the invention are hereinafter more fully described and claimed, and the preferred form of construction of a trousers hanger embodying my invention is shown in the accompanying drawing in which—

50 Fig. 1 is a perspective view showing my improved trousers hanger in its simpler form.

Fig. 2 is a perspective view showing an adjustable form of my improved trousers hanger adaptable for use with greater or less widths of trouser 55

leg and showing my improved clamping means therefor.

Fig. 3 is a perspective view showing one of the adjustable elements shown in Fig. 2.

Fig. 4 is a section taken on line 4—4 of Fig. 2 indicating the position of the trousers thereon.

Fig. 5 is a section taken on line 5—5 of Fig. 2.

In the simpler form of the device shown in

Fig. 1, I provide two metal strips 1 and 2 having

the return bent ends 3 and 4 for the strip 1 and

bent ends 5 and 6 for the strip 2. These return

bent ends of the two strips use inwardly inclined

relative to the respective strips and the terminal

ends 7 of each of the return bent portions are

outturned. These bent ends therefore provide 15

what may be termed a pair of pockets on the

respective opposite sides of the device which are

open toward each other and the terminal bent

ends provide for pressure engagement of the

goods with the respective strips. Centrally be-

tween the ends of the strips there is preferably

provided a groove extending transversely thereof

and the grooves of the two strips are in regis-

tration and receive the tang 8 of the hook element

9 by means of which the device may be supported

in place. These strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

20 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

25 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

30 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

35 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

40 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

45 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

50 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

55 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

60 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

65 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

70 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

75 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

80 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

85 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

90 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

95 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

100 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

105 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips as shown, two pairs

of trousers may be suspended in inverted relation

in the device formed as shown in Fig. 1. These

110 strips 1 and 2 are formed of

spring metal and the opposite edges of a trousers

leg is introduced between the return bent por-

tions 4 and 1 and 3 and 1 on one side of the body

and the other leg may be introduced into the

recesses formed between the return bent end

5 and 1 and 6 and 1 on the opposite side of the

body. With the two strips

to form a rectangular housing 11 and this housing is centrally apertured to receive the tang 12 of the hook element 13. This housing may be formed of any appropriate sheet material and not necessarily of spring metal. The garment clamping portions are indicated in Fig. 3 as having a body portion 14 that is insertible in the recess of the housing 11 with the similar body portion 15 of a like element. These are slidable in the 10 housing and the portions 14 and 15 are of such length that when moved into the housing 11 until the end of the housing engages the end 16 of the garment engaging element, the terminal end 17 does not quite engage the tang 12 of the 15 hook element 13.

It will be seen in Fig. 2 that there are two garment engaging or clamping elements placed back to back with the bodies 14 and 15 in the housing element 11. These body portions 14 and 20 15 of the clamping device are a sufficiently tight fit in the central housing portion 11 as to normally remain in position except under considerable pressure.

A feature of the clamp elements is that the 25 body 16, as shown in Fig. 3, has an inturned portion 18 and the end 19 thereof is then return bent at an angle to or parallel with the portion 18 and the portion 14. The point of connection between the portions 18 and 19 of the clamp is 30 outturned as at 20 to form a wide entrance or throat into which the edges of the trousers legs are introduced and the portion 19 thus moved outwardly and to practically parallel relation with the body portion 14 or 15 of the device and 35 this applied pressure practically equally throughout the length of the return bent end 19. Each end of the member 11 is provided with a pair of clamping devices as illustrated in Fig. 2 and the trousers ends may be introduced thereinto after 40 the manner heretofore described in connection with the construction shown in Fig. 1. In either form of the invention, the cuffs or the leg portions below the cuffs, when in the inverted relation in the hanger, may be introduced into the 45 clamping elements. The form of the trousers clamping means shown in Figs. 2 and 3 can be incorporated in the hanger construction involving the two strips as shown in Fig. 1.

The trousers hanger is shown as being dual 50 in character. However, a single strip having a tang portion or other means provided for supporting the same and having the clamping end portions may be utilized without departing from the spirit and scope of this invention.

55 While I have shown the spring clamping portions 19 of Figs. 2 and 3 as extending at an angle to the adjacent body portion 14 for instance, it is pointed out that the invention is not confined to such angular disposition of the ends 60 19 extending inwardly of the recesses as they might conveniently lie parallel or in contact with the respective body portion and other changes may be made in the specific structure shown

without departing from the spirit and scope of the invention as set forth in the appended claims.

While I have described the device as a trousers hanger, it is pointed out that the device may be used for the hanging of various types of garments, toweling or other sheet like material by merely introducing the opposite edges or portions of the article to be suspended into the clamping elements. Thus the device is of utility in the hanging of various characters of articles.

From the foregoing description it is believed evident that the various objects of the invention are attained by the structures described.

Having thus fully described my invention, its utility and mode of operation, what I claim and desire to secure by Letters Patent of the United States is—

1. A hanger for suspending trousers in inverted position by the leg ends, comprising two flat sheet metal strips secured together in face to face relation and each having return bent ends in opposed relation to and spaced from the body of the respective strips providing oppositely disposed pockets on each side of the device each opening toward the center, said strips at their centers being formed with opposed transverse grooves, and a hanger element having a tang secured in the opposed grooves by securing the strips together.

2. A hanger for suspending trousers in inverted position by the leg ends comprising two flat sheet metal strips secured together in face to face relation and each having its end portions in return bent relation therewith and inwardly inclined from the bend toward the respective strip with the end in spaced relation, the terminal ends being outbent and the bent end portions of the two strips providing oppositely disposed pockets on each side of the device opening toward the center, and a hook member having a tang secured to the strips centrally between the bent ends.

3. In a hanger for suspending trousers in inverted position by the leg ends, a flat sheet metal strip having a return bent portion at one end in spaced relation relative to the body and said return bent portion having a return bent part terminating in the space between the bent end portion and body and being inclined in respect to the body.

4. In a hanger for suspending trousers in inverted position by the leg ends, a flat sheet metal strip having a return bent portion at one end inwardly inclined in respect to the body and in spaced relation therewith, said return bent portion being outwardly bent at a distance from the terminal end and the end portion again being return bent to position in the space between the body of the bent end and the body of the strip, the said end portion of the return bent end in said space being inwardly inclined toward the body.

WILLARD H. BAUGH.
